UNITED STATES PATENT OFFICE

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS

SHOCK-ABSORBING SOCKET FOR VACUUM TUBES

Application filed November 23, 1925. Serial No. 70,789.

My invention relates to shock absorbing sockets for vacuum tubes.

One of the objects of my invention is to provide a shock absorbing socket which will be effective in preventing vibration from interfering with the operation of the tube and which will be durable and efficient.

In the drawings in which an embodiment of my invention is illustrated—

Figure 1 is a plan view of a shock absorbing socket;

Fig. 2 is a side elevation of the socket;

Fig. 3 is a bottom view of the socket;

Fig. 4 is a plan view of the contact supporting member and springs;

Fig. 5 is a side view of the construction shown in Fig. 4;

Fig. 6 is a section on the line 6—6 of Fig. 1;

Fig. 7 is a bottom view of the positioning shield; and

Fig. 8 is a section on the line 8—8 of Fig. 7 showing also the contacts and supporting member.

Referring to the drawings in detail, the construction shown comprises an insulating base or support 10, a yieldingly mounted contact supporting member 11 of insulating material, a plurality of combined spring support and contact members 12 secured both to the contact supporting member 11 and to the insulating base 10, and an insulating shield and positioning member 13 secured to the contact supporting member and having a plurality of spaced apertures 14 for receiving the contact pins on the vacuum tube and guiding them into engagement with the spring contact members.

The insulating base is provided with four spacing legs 15 formed integrally therewith for engaging a suitable support. The combination spring and contact members 12 are secured to the contact supporting member 11 by means of eyelets 16. The contact positioning shield is secured to the contact supporting member by means of a screw 17 extending through the contact supporting member and threaded into the shield. The shield is recessed at 18 to receive the upwardly extending spring contacts 19, each of which is provided with a downwardly turned

extension 20 as shown in Fig. 6, the tip of which engages the shield 13 to support the contact laterally. The spring portions 21 are secured to the insulating base by means of screws 22 extending through the springs 55 and base. Each of these screws may be provided with a binding nut 23, if desired. Each of the springs may be provided with an extension tip 24 to provide a soldering connection for the wires, if desired.

It will be seen that the spring contact members 12 are so arranged and designed with respect to the apertures 14 that they act on the contact pins of the inserted tube in such manner as to tend to cause the tube to 65 rotate about its axis and thus force these pins against the opposite supporting surfaces of the apertures 14.

In order to position the shield with respect to the contact supporting member, the 70 contact supporting member is provided with a notch 25 leading from the central opening which receives a correspondingly shaped boss 26 (Figs. 4 and 7) on the lower side of the shield. The apertures in the shield are 75 of different sizes to ensure that the tube is inserted in the proper position.

I claim:

1. A shock absorbing socket construction for vacuum tubes comprising an insulating support, an insulating positioning shield having spaced apertures to receive and position the electrodes of the tube, means for yieldingly supporting said shield with respect to said support, said shield having a 80 portion overlying said support to limit the downward movement of the shield, a stop member, means for securing said stop member to said shield, said stop member having a portion underlying said support to limit 90 the upward movement of the shield, said shield and said member forming a unitary support and electrode engaging contacts mounted on said unitary support and extending adjacent said spaced apertures, said 95 spring contact being laterally yieldable and engageable with the side of the electrode.

2. A shock absorbing socket construction for vacuum tubes comprising an insulating support, an insulating positioning shield 100

having spaced apertures to receive and position the electrodes of the tube, means for yieldingly supporting said shield with respect to said support, said shield having a portion overlying said support to limit the downward movement of the shield, a stop member, means for securing said stop member to said shield, said stop member having a portion underlying said support to limit the upward movement of the shield, said shield and said member forming a unitary support, and electrode engaging contacts mounted on said unitary support and extending adjacent said spaced apertures.

15 3. A shock absorbing socket construction for vacuum tubes comprising an insulating support, an insulating positioning shield having spaced apertures to receive and position the electrodes of the tube, means for yieldingly supporting said shield with respect to said support, said shield having a portion overlying said support to limit the downward movement of the shield, a stop member, means for detachably securing said stop member to said shield, said stop member having a portion underlying said support to limit the upward movement of the shield, said shield and said member forming a unitary support, and electrode engaging contacts mounted on said unitary support and extending adjacent said spaced apertures.

4. A shock absorbing socket construction for vacuum tubes comprising an insulating support, an insulating positioning shield having spaced apertures to receive and position the electrodes of the tube, means for yieldingly supporting said shield with respect to said support, said shield having a portion overlying said support to limit the downward movement of the shield, a stop member, means for securing said stop member to said shield, said stop member having a portion underlying said support to limit the upward movement of the shield, said shield and said member forming a unitary support, and electrode engaging contacts mounted on said stop member.

5. A shock absorbing socket construction for vacuum tubes comprising an insulating support, an insulating positioning shield having spaced apertures to receive and position the electrodes of the tube, means for yieldingly supporting said shield with respect to said support, said shield having a portion overlying said support to limit the downward movement of the shield, a stop member, means for securing said stop member to said shield, said stop member having a portion underlying said support to limit the upward movement of the shield, said shield and said member forming a unitary support, and electrode engaging contacts mounted on said stop member, said shield being recessed to receive said contacts.

6. A shock absorbing socket for vacuum tubes, comprising a tube holder having a plurality of apertures for receiving the tube electrodes, and means for yieldingly supporting said holder comprising a plurality of leaf spring members, each having a horizontal spring portion for absorbing shocks, and a vertical laterally yieldable contact portion integral therewith extending adjacent one of said apertures for engaging a tube electrode, said contact portion being provided with a downwardly turned tip lying back of the contact portion and engaging the holder to support the contact laterally.

7. A cushion socket construction for vacuum tubes comprising an insulating base having an opening therethrough, an insulating support extending across said opening, tube terminal engaging contact members secured to said insulating support, spring conductor members connecting said base and support providing a yielding mounting for said support and electrical connections for said contacts, and an insulating housing and positioning member secured to said insulating support and extending across said opening, and having recesses in which said contacts are housed, and entrance openings for guiding the tube terminals into engagement with the socket contacts, said housing and positioning member having a portion overlying said base to limit the yielding movement in one direction.

8. A cushion socket construction for vacuum tubes comprising an insulating base having an opening therethrough, an insulating support extending across said opening, tube terminal engaging contact members secured to said insulating support, spring conductor members connecting said base and support providing a yielding mounting for said support and electrical connections for said contacts, and an insulating housing and positioning member secured to said insulating support and extending across said opening, and having recesses in which said contacts are housed, and entrance openings for guiding the tube terminals into engagement with the socket contacts, said insulating support having a portion underlying said base to limit the yielding movement in one direction.

9. A cushion socket construction for vacuum tubes comprising an insulating base having an opening therethrough, an insulating support extending across said opening, tube terminal engaging contact members secured to said insulating support, spring conductor members connecting said base and support providing a yielding mounting for said support and electrical connections for said contacts, and an insulating housing and positioning member secured to said insulating support and extending across said opening, and having recesses in which said contacts are housed, and entrance openings for guiding

the tube terminals into engagement with the socket contacts, said housing and positioning member having a portion overlying said base to limit the yielding movement in one direction, said insulating support having a portion underlying said base to limit the yielding movement in the other direction.

10. A cushion socket construction for vacuum tubes comprising an insulating base having an opening therethrough, an insulating plate extending across said opening, tube terminal engaging contact members secured to said insulating plate, spring conductor members connecting said base and plate providing a yielding mounting for said plate and electrical connections for said contacts, and an insulating housing and positioning member secured to said insulating plate and extending across said opening, and having recesses in which said contacts are housed, and entrance openings for guiding the tube terminals into engagement with the socket contacts, said housing and positioning member having a portion extending through said opening into engagement with said plate.

11. A cushion socket construction for vacuum tubes comprising an insulating base having an opening therethrough, a plurality of wiring terminals mounted on said insulating base, an insulating support adjacent the underside of said insulating base extending across said opening, a plurality of combination contact and spring conductor members, each comprising a spring conductor portion secured to said insulating support and extending between said insulating base and insulating support and lying substantially in a plane transverse to the axis of the socket and secured to said insulating base, adjacent one of said wiring terminals respectively and electrically connected with said wiring terminals respectively and each comprising also a contact portion extending upwardly from said insulating support and having its tip bent downwardly, and an insulating housing and positioning member secured to said insulating support and extending across said opening adjacent the upper side of said base, said housing and positioning member having a plurality of recesses therein to receive and house said vertical contact portions respectively, and having a plurality of entrance openings affording access to the contacts in said recesses respectively, each of said recesses being partly to one side of said entrance opening whereby the contacts on the tube are directed to slide downwardly alongside and in engagement with the vertically extending contact portions, each of said downwardly bent tips engaging a wall of its recess to force the vertically extending contact portion over against another wall of said recess, said insulating housing and positioning member having its main body portion spaced from said flat insulating support and having a

central boss engaging said flat support, said flat support having an opening therein and a screw extending through said opening, and having a threaded engagement with said boss, said flat plate having a portion underlying the insulating base to limit the upper movement of the plate and the housing member secured thereto, and said housing member having a portion overlying said base to limit the downward movement of the housing member and the flat support secured thereto.

12. A cushion socket construction for vacuum tubes comprising a plurality of integral sheet metal members, one for each tube terminal, each metal member comprising a leaf spring portion extending transversely of the axis of the tube for yieldingly supporting the tube, a tube terminal engaging contact portion extending substantially parallel to the axis of the tube, and a spring tip portion bent back to lie substantially behind and opposite the terminal engaging portion, and an insulating, housing, and positioning member having recesses in which said contact and tip portions are housed, and having entrance openings for guiding the tube terminals into engagement with the contact portions, said spring tip portions bearing against portions of said housing member to yieldingly hold the terminal engaging portions in the path of the terminals.

13. A cushion socket for vacuum tubes comprising a stationary insulating support, a yieldingly mounted insulating base having a plurality of recesses therein, one for each tube terminal, a plurality of yieldable contact members for said tube terminals, one in each of said recesses, said contact members being insertable into said recesses from the back side of said insulating base, and a plurality of spring conductor members, one for each contact member, said stationary insulating support having an opening therethrough to provide clearance for at least a portion of said yieldingly mounted base, said spring members being secured to the back side of said insulating support, said tube being insertable into said socket from the front side of said insulating support.

14. A cushion socket for vacuum tubes comprising a stationary insulating support, a yieldingly mounted insulating base having a plurality of recesses therein, one for each tube terminal, a plurality of yieldable contact members for said tube terminals, one in each of said recesses, said contact members being insertable into said recesses from the back side of said insulating base, and a plurality of spring conductor members, one for each contact member, said stationary insulating support having an opening therethrough to provide clearance for at least a portion of said yieldingly mounted base, said spring members being secured to the back side of said insulating support, said tube being insertable

into said socket from the front side of said insulating support, each contact member with its spring conducting member being formed as integral parts of a bent sheet metal strip.

- 5 15. A cushion socket for vacuum tubes comprising a stationary insulating support, a yielding mounted insulating base having a plurality of recesses therein, one for each tube terminal, a plurality of yieldable contact members for said tube terminals, one in each of said recesses, said contact members being insertable into said recesses from the back side of said insulating base, and a plurality of spring conductor members, one for 10 each contact member, said stationary insulating support having an opening therethrough to provide clearance for at least a portion of said yieldingly mounted base, said spring members being secured to the back side 15 of said insulating support, said tube being insertable into said socket from the front side of said insulating support, each contact member with its spring conducting member being formed as integral parts of a bent sheet 20 metal strip, said base comprising a rear member on the back side of said insulating support to which said metal strips are secured and comprising also a face member secured to said rear member and having entrance 25 openings for admitting the tube terminals.

16. A cushion socket construction for vacuum tubes comprising a stationary insulating support, wire terminals mounted thereon, a tube holder and means for yieldingly 30 mounting said tube holder on said insulating support, said stationary insulating support having an opening therein to provide clearance for at least a portion of said tube holder, said tube holder comprising (1) an insulating 35 contact carrier, (2) tube terminal-engaging contacts mounted on said contact carrier, (3) an insulating cover having recesses to receive said contacts and entrance openings for the tube terminals leading to said recesses, said 40 means for yieldingly supporting said tube holder comprising leaf spring means secured to the under side of said stationary insulating support at points spaced circumferentially about the opening therein and also secured to 45 said contact carrier.

17. A cushion socket construction for vacuum tubes comprising a stationary insulating support, wire terminals mounted thereon, a tube holder and means for yieldingly 50 mounting said tube holder on said insulating support, said stationary insulating support having an opening therein to provide clearance for at least a portion of said tube holder, said tube holder comprising (1) an insulating 55 contact carrier, (2) tube terminal-engaging contacts mounted on said contact carrier, (3) an insulating cover having recesses to receive said contacts and entrance openings for the tube terminals leading to said recesses, said 60 means for yieldingly supporting said tube 65 means for yieldingly supporting said tube

holder comprising leaf spring means secured to said stationary insulating support at points spaced circumferentially about the opening therein and also secured to said contact carrier.

70 In witness whereof, I have hereunto subscribed my name.

REUBEN B. BENJAMIN.
